AUTOMATIC LOCKING MEANS FOR SQUEEZE ROLLS AND THE LIKE

Donald S. Warner, Williamstown, Mass., assignor to James Hunter Machine Company, North Adams, Mass., a corporation of Massachusetts

Application April 25, 1955, Serial No. 503,737

13 Claims. (Cl. 68—258)

This invention relates to textile-treating apparatus of the type in which a web of material is passed through the nip formed by a pair of squeeze rolls, padder rolls or similar rolls. The invention has particular reference to an improved apparatus of the character described having automatic means for retaining one of the rolls separated from the other when the apparatus is not in use.

Apparatus of the type described, as commonly made, comprises a roll mounted for rotation on a frame, and a second roll mounted for rotation on a pair of levers pivoted on the frame, so that by actuation of the levers the second roll is moved toward or away from the first roll. The levers are connected to a suitable power source which is operable selectively by a control device such as a valve or switch. The control device has a "loading" position wherein the levers are swung in one direction by the power source to move the second roll against the first for normal operation, and a "lift" position wherein the power source swings the levers in the opposite direction to retract the second roll from the first. When the apparatus is shut off, the second roll is returned by gravity against the first roll, where it rests until the apparatus is again placed in operation and the control device moved to the "lift" position.

The present invention has for its principal object the provision of an improved apparatus of this character in which the lever-mounted roll is automatically held separated from the other roll when the apparatus is not in use.

In an apparatus made according to the invention, a locking block is normally disposed in the path of at least one of the levers and is engageable thereby to hold the lever-mounted roll spaced from the other roll. This block is connected to an element for shifting the block out of the lever path, whereby the power source is operable to move the lever-mounted roll against its mating roll. The apparatus also comprises means for connecting the power source to this shifting element through the control device in response to movement of the latter to its "load" position, so that the locking block is automatically shifted out of its lever-locking position whenever the control device is operated to move one roll against the other. Upon movement of the control device to its "lift" position, the locking block is automatically returned into the path of the lever, as by means of a biasing member connected to the block. Thus, when the apparatus is subsequently shut off, the locking block is engaged by the lever to hold the rolls apart independently of the power source.

In its preferred construction, the apparatus comprises two locking blocks, one for each lever, connected to a shifting element in the form of a bar mounted on the frame for longitudinal sliding movement parallel to the roll axes. This bar is operable through a cylinder and

2

piston from a pneumatic power source which also actuates the levers supporting the adjustable roll. The control device is a valve which connects the pneumatic power line to the bar-shifting cylinder in response to movement of the valve to the "load" position wherein the levers are pneumatically operated to move one roll against the other. Movement of the valve to its "lift" position serves to disconnect the bar-shifting cylinder from the pneumatic power line, whereupon the locking blocks are automatically returned into the respective lever paths so as to hold the rolls apart when the apparatus is shut off.

For a better understanding of the invention, reference may be had to the accompanying drawings, in which Fig. 1 is a perspective view of a preferred form of the

15 new apparatus;

Fig. 2 is a schematic view of the apparatus illustrated in Fig. 1, showing its connections to the power source;

Fig. 3 is an enlarged front view of the valve for controlling the connections to the power source;

20 Fig. 4 is a vertical sectional view through part of the apparatus illustrated in Fig. 1, showing the locking blocks associated with the levers, and

Fig. 5 is a schematic view in perspective showing the 25 relationship between the locking blocks and the roll levers.

The apparatus as illustrated comprises a frame 10 having two opposed side sections 11 and 12 for rotatably supporting the rolls, which may be squeeze rolls or the rolls of a padder. As shown, there are two such rolls 30 13 and 14, although it will be understood that at least one additional roll may be provided directly below the lower roll 13, as is common in apparatus of this character. The two rolls 13 and 14 extend between the side frames 11 and 12, and the lower roll 13 is rotatably 35 mounted at its ends in suitable bearings fixed to the respective side frames, the bearing for one end of this roll being located in a bearing housing 13a secured to the side frame 12, as shown in Fig. 1. The upper roll 14 is rotatably mounted at its ends in similar bearings on the free ends of levers 15 and 16 which are pivoted intermediate their ends on the side frames 11 and 12, respectively. As shown in Fig. 1, the lever 16 is mounted on a pivot 16a on the corresponding side frame 12, and the free end of this lever carries a housing 14a for the 40 bearing in which the adjacent end of the upper roll 14 is supported for rotation. It will be understood that the other lever 15 is similarly pivoted on the side frame 11 and carries a similar housing for the other bearing in which the upper roll is mounted.

50 45 It will be apparent from the foregoing that the top roll 14 may be lifted from the bottom roll 13 by depressing the ends of the levers remove from the top roll; and the top roll will return into contact with the bottom roll (or the web of material extending through the nip between these rolls) when the levers are released.

The top roll levers 15 and 16 are adapted to be actuated by piston rods 18 and 19 secured to double-acting pistons 18a and 19a slidable vertically in pneumatic cylinders 20 and 21, respectively. The upper ends of the rods 18 and 19 are pivotally connected to the levers 15 and 16, respectively, at the ends thereof remote from the top roll 14. The cylinders 20 and 21 are connected to a pneumatic power source 22 in the form of a compressed air line through a valve 23 which serves as a control device. As 60 shown in Figs. 2 and 3, the valve 23 has a "load" position in which it connects the air line 22 to the lower end portions of the cylinders through a branch pipeline 24. The control valve 23 also has a "lift" position in which it

connects the compressed air line 22 to the upper portions of the cylinders 20 and 21 through a branch pipeline 25. Thus, when the valve 23 is moved to its "lift" position by manual operation of its handle 23a, compressed air is admitted to the upper portions of the cylinders from the air line 22, and the lower portions of these cylinders are connected to atmosphere through a vent (not shown) in the valve 23, whereby the pistons 18a and 19a are forced downward so as to lift the top roll 14 from the bottom roll by swinging the levers 15 and 16 in one direction about their pivots. With the top roll thus spaced from the bottom roll, the web material (not shown) may be drawn freely between the rolls, for purposes well known in the art. Upon movement of the valve 23 to its "load" position, compressed air is admitted into the lower portions of the cylinders from the air line 22, and the upper portions of these cylinders are vented to atmosphere through the branch line 25 and valve 23. Consequently, the pistons 18a and 19a are forced upward so as to swing the levers 15 and 16 in the opposite direction about their pivots, thereby returning the top roll 14 into engagement with the bottom roll 13 (or the web material extending through the nip formed by these rolls). The apparatus is now ready for operation, the top roll being held against the bottom roll under the pressure exerted by the pneumatic power source 22 through the pistons 18a and 19a and the respective levers 15 and 16.

The valve 23, as shown in Fig. 3, also has an "off" position wherein it disconnects the compressed air line 22 from both ends of the cylinders 20 and 21. Valves functioning as herein described are well known in the art. For example, such a valve is described and illustrated in U. S. Patent No. 2,138,397 of E. Cannity, dated Nov. 29, 1938. Referring to said patent, it discloses a valve 63 corresponding to my valve 23 and having a fluid supply pipe 22, a waste pipe 67 corresponding to the previously mentioned vent (not shown) in my valve 23, and conduits 59 and 61 corresponding to my pipe lines 25 and 24, respectively, leading from the valve to the opposite ends of the cylinders. The valve-handle 69 of said patent corresponds to the valve-handle 23a of my valve 23.

The locking means of the present invention serve to prevent the gravity return of the top roll 14 against the bottom roll 13 when the apparatus is shut off. That is, without such locking means the movement of valve 23 from its "lift" position to its "off" position would result in the upper roll descending by gravity into contact with the lower roll due to leakage of compressed air from the pneumatic system; and this action would occur even when the control valve is left in its "lift" position, if the air pressure in line 22 is not maintained when the apparatus is not in use.

The locking means as illustrated, comprise a pair of locking blocks 27 and 28 normally positioned in the paths of the levers 15 and 16, respectively. As best shown in Fig. 4, the side frames 11 and 12 are hollow, and the blocks 27 and 28 are disposed within the respective side frames where they are substantially in contact with overlying solid sections 11a and 12a, respectively, of these frames. The levers 15 and 16 are also pivotally mounted within the respective side frames and are so located that the end portions thereof connected to the piston rods 18 and 19 are directly under the locking blocks 27 and 28 when the latter are in their normal positions.

The locking blocks 27 and 28 are connected to the ends of a hollow rod or bar 29 extending through openings 11b and 12b in the opposing faces of the respective side frames 11 and 12. At one end, the bar 29 carries a projection 29a extending through a removable cover plate 11c, on the hollow side frame 11. At its opposite end, the bar 29 is provided with a fitting 29b to which a piston rod 30 is adjustably connected. As shown, the rod 30 has a threaded end which is screwed into the fitting 29b, the rod being held in its adjustable position in the fitting by means of a nut 30a. The rod 30 extends outward through

an opening in the side frame 12 and into a pneumatic cylinder 31, where it is connected to a piston 32. A compression spring 33 is coiled around the rod 30 in the cylinder 31 and serves as a biasing member for urging the piston 32 outward against a stop (not shown) in the cylinder. In this stopped position of the piston 32, the locking blocks 27 and 28 are located in the paths of the respective levers 15 and 16, so that the blocks directly overlie these levers when the top roll 14 is in its raised position. The cylinder 31 is secured to the side frame 12 in any suitable manner.

Rotation of the bar 29 is prevented by means of a guide pin 34 secured to the side frame 11 and projecting into an opening 27a in the locking block 27. It will be understood that the bar 29 is mounted for longitudinal sliding movement parallel to the axes of the rolls 13 and 14, the guide pin 34 extending parallel to these axes so as to accommodate such sliding movement. The bar 29, which constitutes a shifting element for the locking blocks, is 15 20 25 30 35 40 45 50 55 60 65 70 75 80 85 90 95 100

slidable within a stationary tube 35 secured at its ends to the opposing faces of the side frames 11 and 12 around the openings 11b and 12b. The cylinder 31 is connected at its outer end to the compressed air line 22 through the control valve 23 by means of a pipe line 37 leading from the branch line 24. Consequently, when the valve 23 is moved to its "load" position, compressed air is admitted to the lower portions of the cylinders 20 and 21 and also to the outer portion of the cylinder 31. As a result, the piston 32 is moved to the left (Fig. 4) against the action of spring 33 so as to move the shifting element 29 and the locking blocks 27 and 28 to the left, whereby the locking blocks are displaced from the paths of the respective levers 15 and 16, as indicated by the broken lines in Fig. 4. This displacement of the locking blocks will occur before the levers 15 and 16 can engage the blocks, since movement of the top roll 14 from its fully raised position (where it is held when valve 23 is in the "lift" position) is delayed by the restriction of the escape of compressed air from the upper portions of cylinders 20 and 21 through the restricted vent opening in valve 23. Thus, when valve 23 is moved from the "lift" to the "load" position, the restriction on the venting of air from the upper portions of cylinders 20 and 21 will delay the lowering of top roll 14 so that by the time the power-operated ends of levers 15 and 16 have been raised to the positions shown in Fig. 4, the locking blocks 27 and 28 will have been displaced by piston 32 from the paths of these levers, so that the top roll can be forced downward against the bottom roll. The positions which the locking blocks occupy when they have been thus displaced from the paths of the levers are indicated by the broken lines in Figs. 4 and 5.

Upon movement of the control valve 23 from the "load" to the "lift" position, the top roll 14 is raised 55 60 65 70 75 80 85 90 95 100 pneumatically from the bottom roll through the action of the pistons 18a and 19a in swinging the levers in the corresponding direction on their pivots, as previously described. At the same time, the shift cylinder 31 is disconnected from the air line 22, since the "load" line 24 to which cylinder 31 is connected is now vented to atmosphere through the restricted vent opening in valve 23. Consequently, the spring 33 moves the shifting element 29 and the locking blocks 27 and 28 to the right, as shown in Figs. 4 and 5, whereby the locking blocks are returned to their locking positions above the adjacent ends of the levers.

When the control valve 23 is moved from the "lift" to the "off" position, the top roll 14 will slowly descend by gravity from its fully raised position, as previously 70 75 80 85 90 95 100 described. However, engagement of the top roll with the bottom roll is now prevented by the locking blocks 27 and 28, which are engaged by the adjacent ends of levers 15 and 16 (Figs. 4 and 5) while the top roll is still raised somewhat from the bottom roll. Accordingly, throughout the period in which the apparatus is not in

use, the locking blocks are interposed between the levers 15 and 16 and the overlying solid sections 11a and 12a of the side frames, so that the rolls 13 and 14 are held apart.

I claim:

1. In an apparatus of the character described having a frame, a roll mounted for rotation on the frame, a pair of roll levers pivoted on the frame, a second roll mounted for rotation on said levers and extending in substantially parallel adjacent relation to the first roll, a power source connected to the levers, and a control device connected to the power source for selectively operating the power source to swing each lever back and forth through a path and thereby move the second roll into and out of engagement with the first roll, the combination of a bar extending substantially parallel to the roll axes and mounted on the frame for longitudinal sliding movement, a pair of locking blocks on the bar normally disposed in the paths of the respective levers and engageable thereby to hold the second roll spaced from the first roll, the power source being operable on the levers to swing them in one direction away from the blocks and thereby increase the spacing between the rolls, and an element connected to the bar for shifting it longitudinally to move the blocks out of the paths of the levers, whereby said power source is operable on the levers to swing them in the opposite direction and thereby move the second roll against the first roll.

2. The combination according to claim 1, comprising means operatively connecting the power source to the shifting element through said control device.

3. The combination according to claim 1, comprising means operatively connecting the power source to the shifting element through said control device, the control device having a first position wherein the power source swings the levers to move the second roll away from the first roll, and a second position wherein the power source operates said shifting element to move the blocks out of the paths of the levers and swings the levers to move the second roll against the first roll.

4. The combination according to claim 1, comprising means operatively connecting the power source to the shifting element through said control device, the control device having a first position wherein the power source swings the levers to move the second roll away from the first roll, and a second position wherein the power source operates said shifting element to move the blocks out of the paths of the levers and swings the levers to move the second roll against the first roll, the control device also having a third position wherein the power source is inoperable on the levers, the combination including also a biasing member operatively connected to the bar for shifting it longitudinally to return the blocks into the lever paths in response to movement of the control device to its third position.

5. In an apparatus of the character described having a frame including two opposed sections, a roll extending between said sections and mounted thereon for rotation, a pair of roll levers pivoted on the respective frame sections, a second roll mounted for rotation on said levers and extending in substantially parallel adjacent relation to the first roll, a power source, a first connection from said source to the levers for swinging each lever back and forth through a path, and a control device connected to the power source and having a first position wherein the power source swings the levers in one direction to move the second roll away from the first roll, a second position wherein the power source swings the levers in the opposite direction to move the second roll against the first roll, and a third position wherein the power source is inoperable on the levers, the combination of a pair of locking blocks normally disposed in the paths of the respective levers and engageable thereby to hold the second roll spaced from the first roll independently of said first connection, an element connected

to the blocks for shifting them out of the paths of the levers, whereby the power source is operable in said second position of the control device to move the second roll against the first roll, and means operatively connecting the power source to the shifting element through said control device.

6. The combination according to claim 5, in which said connecting means are arranged to connect the power source to the shifting element through the control device in said second position thereof.

7. The combination according to claim 5, comprising means operatively connected to the locking blocks for returning them into the paths of the levers in response to movement of the control device from its second position.

8. The combination according to claim 5, comprising a bar mounted on said frame sections for longitudinal sliding movement substantially parallel to the roll axes, the locking blocks being mounted on the bar, and the bar being connected to said shifting element.

9. In an apparatus of the character described having a frame including two opposed sections, a roll extending between said sections and mounted thereon for rotation, a pair of roll levers pivoted on the respective frame sections, a second roll mounted for rotation on said levers and extending in substantially parallel adjacent relation to the first roll, a cylinder and a double-acting piston therein connected to one of the levers, a fluid pressure source, and a control valve connecting said source and cylinder and adapted to be positioned selectively to admit pressure fluid into one or the other end portion of the cylinder for moving the second roll toward or away from the first roll by swinging the levers back and forth through a path, the combination of a locking block normally disposed in the path of said one lever and engageable thereby to hold the second roll spaced from the first roll, a second cylinder and a piston therein connected to the locking block for moving the block out of said path, and means for connecting said source to the second cylinder through said valve when the valve is positioned to move the second roll toward the first roll.

10. The combination according to claim 9, comprising means for returning the block into said path in response to positioning of the valve to move the second roll away from the first roll.

11. In an apparatus of the character described having a frame, a pair of rolls mounted for rotation on the frame and disposed in substantially parallel adjacent relation to each other, one of the rolls being movable toward and away from the other roll, a power source, and an operating connection from the power source to said movable roll and including a lever pivoted on the frame and through which the power source is operable to displace the movable roll toward and away from the other roll, the combination of a locking block independent of said operating connection and having a locking position in which the block is in the path of and engageable by said operating connection to hold said movable roll spaced from the other roll, an element connected to said block for shifting said block from said path to an unlocking position wherein the power source is operable through said connection to displace the movable roll against the other roll, and a second operating connection from the power source to said shifting element for actuating said element to shift the block to its unlocking position.

12. The combination according to claim 11, comprising biasing means independent of said connections and urging the block toward its locking position.

13. The combination according to claim 11, comprising biasing means independent of said connections and urging the block toward its locking position, and a control device connected to the power source and having a first position wherein said source is operable through said

first connection to displace said movable roll away from the other roll and wherein the source is operable through said second connection to cause said biasing means to hold the block in its locking position, the control device having a second position wherein said source is operable through said first and second connections to displace the movable roll against the other roll and to actuate the shifting element, respectively.
